[57] **CLAIM**

The ornamental design for a transportation container for pourable materials, as shown and described.

DESCRIPTION

FIG. 1 is an isometric view of the design showing the front, top and one side;

FIG. 2 is an isometric view of the design showing the bottom, other side and rear;

FIG. 3 is a side elevational view of the design;

FIG. 4 is a front elevational view of the design;

FIG. 5 is a rear elevational view of the design;

FIG. 6 is a top plan view of the design; and,

FIG. 7 is a bottom plan view of the design.

FIG. 1

FIG. 2

FIG. 7

FIG. 3

FIG. 4

FIG. 5

FIG. 6
